LEGER J. CASTONGUAY, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SHADE-HOLDER.

957,305.

Specification of Letters Patent. Patented May 10, 1910.

Application filed February 26, 1909. Serial No. 480,093.

To all whom it may concern:

Be it known that I, LEGER J. CASTONGUAY, a citizen of the United States of America, residing in the city of Bridgeport, in the county of Fairfield, in the State of Connecticut, have invented certain new and useful Improvements in Shade-Holders, of which the following is a specification.

My invention relates to shade holders for incandescent electric lamps, more particularly shade holders adapted for use with tungsten or other high efficiency metallic filament lamps. Such shade holders generally comprise a conical shell secured at its smaller end to the lamp socket and having suitable means by which the flanged neck of the shade may be secured in or detached from the larger open end of the shell.

The object of my invention is to construct such a shade holder that the shade may be readily applied or removed but will be securely held while it is in place.

In the accompanying drawings Figure 1 is a side elevation of my improved shade holder; Fig. 2 is a sectional plan on the line 2-2, Fig. 1; Fig. 3 is a like sectional view but with the spring clips in position to engage and hold the shade.

In Fig. 1, the conical shell A of the shade holder is shown as secured at its upper smaller end to the lamp socket B between the two ribs b on the socket shell. At its larger lower end, the shell is formed with a flanged mouth C of a size to receive freely within it the flanged neck of the shade. Within this flanged mouth, I provide two spring clips D, D, each secured at one end, as by riveting, to the shell, and having its main body part lying within the mouth of the shell, while the free end of each spring clip is bent and passes more or less radially outward through a horizontal slot e in the shell. Adjacent to the point where each spring clip D is secured to the shell, the wire

has an inward bend α to take under the flanged neck of the shade. At their outer ends, the two spring clips preferably are bent up to form small handles d standing vertically in positions to be pressed together by the finger and thumb. The slots e, e, through which these spring clips pass are formed with notches or catches e^1 at their inner ends, such that the clips when pressed toward each other may be engaged in these catches, and held thereby in the positions shown in Fig. 3. When not so held, the spring clips are pressed by their elasticity outward against the inner walls of the shell, and then the flanged neck of a shade may be introduced into the shell over the bends α . If then the projecting handles d be pressed together, and the spring clips latched into the notches e^1 , the clips will have engaged and will securely hold the flanged neck of the shade S, until the clips are released again.

I claim as my invention—

A shade holder, comprising a shell adapted to be secured to a socket and having two slots with notches, near its mouth where it receives the flanged neck of the shade, in combination with two spring clips each secured at one end to the shell and adapted when free to lie against the inner wall of the latter, and having adjacent to its secured end an inward bend α and its free end projecting through one of said slots, said spring clips adapted when their free ends are pressed toward each other to be engaged in said notches and to engage and hold the shade.

In testimony whereof I have signed my name to this specification, in the presence of two subscribing witnesses.

L. J. CASTONGUAY.
